CUP AND SAUCER SUPPORT

Ernest R. Hanson, New Britain, Conn.

Application October 21, 1948, Serial No. 55,750

3 Claims. (Cl. 248—199)

1

This invention relates to a cup and saucer support and more generally to such devices as are adapted to support a cup and saucer for display purposes.

An object of the invention is to provide such a support for attractively displaying cups and saucers in homes, store windows and other places where such display is desired.

A further object of this invention is to provide a cup and saucer support which is simple in its construction, inexpensive to manufacture and adapted to securely support the cup and saucer in an attractive position.

Further objects and advantages of this invention will be more clearly understood from the following description and from the accompanying drawing in which:

Fig. 1 is an elevational plan view of my novel cup and saucer support.

Fig. 2 is an elevational side view thereof illustrating the improved construction of my novel support.

Fig. 3 is an elevational front view thereof.

Fig. 4 is an elevational side view of said support illustrating the positioning of a cup and saucer thereon.

In the embodiment of the invention as illustrated in the drawings, my novel cup and saucer support may comprise a symmetrical wire frame including side members 4—4, having front leg portions 5—5 with forwardly extending loops at the free ends thereof forming front feet on my novel support. The wire forming the leg portions 5—5 is bent rearwardly at the top thereof to form the loops 6—6 which extend rearwardly and are formed to provide detents 8 and horizontal rest bars 9—9 for respectively receiving and supporting the edge of a saucer. The said horizontal bars are bent upwardly to form bracing members 10—10 which are bent rearwardly and downwardly at their opposite ends to form near legs 11—11 for the said frame.

The side portions 4—4 are connected by upwardly converging arms 12—12 which extend from the lower ends of each of the said legs 11—11 and are connected in a centrally located loop 13 to which there is connected one end of a suitable expansion spring 14 which has attached to the other end thereof a double hook comprising two loops 16 and 17 opening respectively downwardly and upwardly as clearly illustrated in Fig. 2.

In the use of my improved supporting frame for supporting a cup and saucer, the saucer is first placed in the frame with the edge there-

2

of resting on each of the horizontal bars 9—9 and in the detents 8—8; the bottom of said saucer resting against the bracing members 10—10 as clearly illustrated in Fig. 4. The saucer is securely retained on the support by pressing the downwardly open loop 16 of the hook 15 over the top edge of the saucer 18 and thereby enabling the spring 14 to securely hold the saucer in position on the support. The handle of a cup 19 may then be placed into the upwardly open loop 17 of the said hook and the bowl of the cup allowed to rest on the inner surface of the saucer.

It will be noted that my novel supporting frame is also adapted to hold plates of various sizes and shapes and is therefore not limited to the supporting of a cup and saucer only.

I claim:

1. A cup and saucer support comprising a wire frame including a pair of spaced side members each having a front and a rear leg, means extending between said legs for supporting a saucer by the lower edge thereof, a joining portion extending between said side members; said joining portion comprising a pair of arms converging upwardly from the lower end of said rear legs and forming an attaching portion intermediate the said side members, and resilient means engaging said attaching portion and having a hook at the free end thereof engageable with the upper edge of the saucer for retaining it on the support; the said hook being adapted to also support a cup relatively to the saucer.

2. A cup and saucer support comprising a wire frame including spaced side members having front and rear leg portions, horizontal supporting portions extending rearwardly of said front legs, a bracing portion extending upwardly from said supporting portions, means at the intersection of said supporting portions and front leg portions adapted to receive the edge of a saucer resting against said bracing portion, an upwardly diverging arm extending from each of said rear leg portions and forming a loop at the intersection thereof with the arm of the opposite leg portion intermediate the said side portions, a spring anchored to said loop, and means attached to the free edge of said spring for securing the saucer on said support and supporting a cup relatively thereto.

3. A cup and saucer support comprising a pair of spaced side portions having front and rear leg portions, rearwardly extending loops at the top of said front leg portions; the said loops extending downwardly and forwardly and then

rearwardly into a horizontal rest bar portion and forming a detent at the front end of said bar portion adapted to receive the edge of a saucer, an upwardly inclined bracing portion at the other end of said rest bar portion which extends downwardly from the top thereof to form the said rear leg portion, an inwardly diverging arm on each of said rear leg portions forming a loop at the intersection thereof with the arm of the opposite side portion, a spring anchored by one end to said loop, a hook at the free end of said spring having a double loop forming a downwardly and upwardly open hook, the said downwardly open hook being adapted to fit over the upper edge 15 of the said saucer and the upwardly open hook

being adapted to receive the handle of a cup for supporting the said cup against the inner face of said saucer.
